[57] CLAIM

The ornamental design for a gravity film feed dispenser
or similar article, substantially as shown and described.

DESCRIPTION

FIG. 1 is a side elevational view of our gravity film feed
dispenser or similar article;
FIG. 2 is a plan view thereof;
FIG. 3 is a front elevational view thereof;
FIG. 4 is a rear elevational view thereof;
FIG. 5 is a bottom plan thereof;
FIG. 6 is a cross-sectional view of a modified embodiment
thereof, taken along the line 6—6 of FIG. 7; and
disclosing certain additional details of the design
thereof.
FIG. 7 is a plan view thereof;
FIG. 8 is a front elevational view thereof;
FIG. 9 is a rear elevational view thereof;
FIG. 10 is a bottom plan view thereof; and
FIG. 11 is a perspective view thereof.
